UNITED STATES PATENT OFFICE.

DANIEL E. HENNESSY, OF HOLYOKE, MASSACHUSETTS, ASSIGNOR TO HERBERT W. COWAN, J. LEWIS WYCKOFF, AND EDWARD N. WHITE, TRUSTEES, DOING BUSINESS AS COWAN TRUCK COMPANY.

JACK.

1,381,992.

Specification of Letters Patent. Patented June 21, 1921.

Application filed July 14, 1915. Serial No. 39,729.

To all whom it may concern:

Be it known that I, DANIEL E. HENNESSY, a citizen of the United States, residing at Holyoke, county of Hampden, and State of 5 Massachusetts, have invented certain new and useful Improvements in Jacks, of which the following is a clear, full, and exact description.

This invention relates to jacks, and particularly to the means for effecting the movement of the jack-post of a jack.

A general object of the invention is to provide a simple and powerful mechanically-operated jack.

15 More particularly the invention aims to provide improved means for engaging the jack-post of a jack to effect its movement or to retain it in the position to which it has been moved, which means will be positive 20 and certain in operation and will effectively engage the jack-post at any point within the range of relative movement of said post and said means.

The invention is herein shown as embodied 25 in a jack which is particularly adapted for use in raising the platform of a truck for transporting heavy articles, but it will be understood that the showing is merely illustrative of one application of the invention 30 and is not intended to affect the scope of the protection sought.

An important feature of the invention is the arrangement of two nuts upon a steeply threaded jack-post in such manner that the 35 nuts are alternately held against turning on said post, whereby by relative movements of approach and separation of said nuts a jacking movement of said post is effected.

Other features and important objects of 40 the invention will appear from the following description and claims when considered in connection with the accompanying drawings, in which—

Figure 1 is a plan view of the improved 45 jack, which constitutes the subject-matter of this invention;

Fig. 2 is a side elevation with parts in section, a portion of a truck frame and a platform being shown in this view;

50 Fig. 3 is a longitudinal section;

Fig. 4 is a rear elevation of the jack-releasing means;

Fig. 5 is a bottom plan view of the mechanism shown in Fig. 4;

Fig. 6 is a rear elevation of the jack locking nut; and

Fig. 7 is a rear elevation of the jack operating nut.

As hereinabove suggested, the jack, which is the subject-matter of this invention, is 60 particularly adapted for use with so-called elevating trucks, and for the purposes of this description the jack is shown in connection with the cooperating parts of an elevating truck. This truck may be of the 65 general type disclosed in my copending application, Serial No. 194,591, filed Oct. 3, 1917, and comprises a frame 2 having an upwardly and forwardly arched portion 4, in which the steering-wheel or caster (not 70 shown) has its bearings and a platform 6 arranged for a compound movement of elevation upon the frame, comprising a shifting movement and a lifting movement, the platform being maintained in parallelism to 75 itself throughout this movement. This compound movement may be obtained in any suitable way, as for example by inclined members such as shown in my copending application, Serial No. 194,591, hereinabove 80 referred to.

The jack by which the shifting and lifting movement of the platform 6 is effected is pivotally mounted upon the truck frame 2 so that it may swing about its pivots 8 as the 85 platform is raised, and this jack comprises a jack post 10 having rigidly attached to its outer end a head 12 pivoted between ears 14 on a bracket 16 attached to the underside of the platform 6. The jack post 10 is provided 90 with steep threads or grooves 18, the illustrated jack post having three of these threads. Mounted upon the jack post are two nuts 20 and 22, the nut 20 being threaded 95 upon the jack post, and the nut 22 having two threads which coöperate with two of the three threads 18 of the jack post. The purpose of this difference in the threading of the two nuts will appear hereinafter.

100 It will be noted that the threading of the jack post 10 is so steep that a movement of the jack post through the nuts 20 and 22, or a movement of the nuts 20 and 22 lengthwise of the jack post will cause the nuts to be 105 turned upon the jack post. In order that advantage may be taken of this to effect a longitudinal movement of the jack post, pro-

vision is made for relative movements of approach and separation of the nuts and for alternately holding the nuts against turning. In the illustrated construction the nut 20 is mounted in a bearing member 24, which is carried upon the pivots 8 and is thus free to turn about said pivots during the operation of the jack but is held against movement lengthwise of the frame 2. The nut 20 is provided with a conical clutching surface 26, which coöperates with the correspondingly shaped inner face 28 in the rear end of the bearing member 24. A cylindrical neck portion 30 of the nut 20 is received in a corresponding cylindrical bore 31 in the bearing member 24, said neck portion being threaded at its forward end to receive a nut or collar 32 by which said nut 20 is confined in the bearing member, the collar 32 being so located upon the nut 20 that provision is made for movement of the nut 20 in the bore 31 whereby the clutching surface 26 upon the nut 20 may be moved into and out of engagement with the coöperating surface 28 upon the bearing member 24. This movement of the nut 20 through the bore of the bearing 24 is sufficiently free so that it will be effected by the movement of the jack post. The nut 22, like the nut 20, has a conical clutching surface 34 which coöperates with the correspondingly shaped inner surface 36 in a bearing member 38 for said nut 22. The nut 22, like the nut 20, also has a cylindrical neck portion 40 received in a cylindrical bore 41 in the bearing member 38 and threaded at its forward end to receive a collar 42 which confines said nut in its bearing. The bearing member 38 is provided with trunnions 44 which receive links 46 pivotally connected at 48 to a lever 50, of the second class, fulcrumed at 52 upon a bracket 54 at the forward end of the truck frame 2. Oscillation of said lever 50 about its fulcrum 52 effects, through the links 46, a reciprocation of the bearing member 38 upon the jack post 10. The nut 22, like the nut 20, is confined in its bearing member with provision for limited movement lengthwise of said member, whereby the surface 34 upon the said nut is moved into and out of clutching relation to the surface 36 on said member. From the foregoing description it will be seen that when the bearing member 38 is moved toward the rear of the truck, that is, toward the right in each of the figures in which it is shown, it will be brought into clutching relation to the nut 22 and will not only carry the nut with it but will also prevent it from turning upon the jack post 10, thereby causing the jack post also to be moved with said bearing member. Such movement of the jack post moves the nut 20 out of clutching relation to its bearing member 24, whereby the nut 20 is free to turn upon the jack post as the jack post is moved

through it. When the bearing member 38 is again moved toward the front of the truck, that is, toward the left in each of the figures in which it is shown, it moves out of clutching relation to the nut 22, thus permitting this nut to turn freely upon the jack post. At the same time the tendency of the jack post to move back to its original position causes the nut 20 to be moved into clutching relation to the bearing member 24, whereby this nut is prevented from turning and the jack post is thus held substantially in the position to which it has been moved by the movement of the bearing member 38 toward the rear of the truck. The jack post being held by the nut 20, the nut 22 is moved to a new position upon the jack post, and when the bearing member 38 is again moved toward the rear of the truck, the jack post is advanced still farther in its platform-lift direction. 85

A lever 56, fulcrumed at 58 upon the arched portion 4 of the truck frame, has a pin 60 received in a slot 62 in the upper end of the lever 50 and is provided with a stop 64 arranged to engage a stop 66 upon the truck frame to limit the rearward movement of said lever. The lever 56 may be connected in any suitable manner to the handle by which the truck is drawn and steered, whereby it may be operated by a forward and backward movement of said handle to effect the oscillation of the lever 50, a suitable connection to the draft handle of the truck being shown in my copending application Serial No. 194,591. 95

It will be apparent that in order to release the jack to permit the load platform to be lowered, it is necessary that both the nut 20 and the nut 22 be permitted to turn freely upon the jack post 10. Means now to be described has been provided for effecting the release of the jack, such means being preferably arranged to be operated by the foot of the operator. The means operating to hold the nut 20 in released position will first be described. 105

The bearing member 24 for the nut 20 has a cylindrical extension 68 on the forward side of its pivotal axis, which is threaded to receive a cap 70, having a central bore through which the jack post 10 moves, and having a stud 72 projecting from its front face below said jack post. The stud 72 serves as a crank pin by which the cap 70 may be screwed back and forth upon the cylindrical part 68 of the bearing member. Between the inner face of the cap 70 and the forward end of the nut 20 is a washer 74. When the parts are in the position shown in Fig. 3, it will be seen that the washer 74 fills the space between the end of the nut 20 and the inner face of the cap 70, the nut 20 being in its released condition, thus preventing the nut from moving into 115

clutching relation to its bearing member. This is the released position of these parts and is not the normal position. In the normal position of these parts there is sufficient space between the inner face of the cap 70 and the seat for the collar 32, so that the nut 20 may move freely into and out of clutching relation to the bearing member 24.

10 The means for moving the cap 70 into the position shown in Fig. 3 comprises a bell-crank lever 76 having on one arm an upwardly extending forked portion 78 which embraces the stud 72, the other arm 80 of the bell-crank lever being bent upwardly out of the plane of the first mentioned arm, and having a universal joint connection 82 with a link or rod 84 connected at its other end to the lower arm of a treadle lever 86, 20 fulcrumed at 88 upon the truck frame. A spring 90 confined between the collar 92 on the rod 84, and an upstanding portion 94 of the truck frame, tends to hold the treadle lever 86 in its elevated position and to hold the bell-crank 76 in such position that the cap 70 is maintained in the jack-operating position. In order that the nut 22 may also be held in such relation to its bearing member 38 that it will turn freely on the jack post as said 25 post moves toward the platform-lowering position, an abutment 98 is provided against which the forward end of this nut strikes when the carrier 38 is moved to its extreme forward position, thus effecting a relative movement of the carrier and nut into unclutching relation.

In order that the operator may retard the lowering of the platform, braking means have been embodied in the jack-releasing 40 means, the illustrated braking means comprising a conical friction surface 96 upon the collar 32, which coöperates with a correspondingly shaped friction surface upon the inside of the bearing member 24. These 45 two surfaces are preferably so shaped that they do not constitute a locking couple. It will be seen that as the operator presses his foot upon the treadle portion 87 of the treadle lever 86, he effects the turning of the cap 70 to release the locking couple 20, 24, and further depression moves the friction surface 96 into contact with the friction surface on the member 24, thereby retarding the turning of the nut 20. The degree of the retarding action depends obviously upon the pressure exerted upon the treadle 87.

In order to limit the lifting movement of the jack, a plug or stop 97 is located in that 60 one of the threads 18 of the jack-post 10 which has no corresponding thread in the nut 22. The stop 97 will thus pass through the nut 22 and into engagement with the front end of the thread in the nut 20 which 65 travels in said groove or thread in which

the stop is located. It will thus be seen that the jack can be extended by the operation of the nut 22 substantially to the end of the jack-post 10, and that the stop 97 will prevent over-extension or movement of the 70 jack-post 10 out of operative relation to the nuts.

What I claim as new is:—

1. A jack comprising, in combination, a jack-post having a thread thereon so inclined to its axis that a nut screwed upon said thread may be turned by relative movement of said post and said nut along said axis, a nut on said post, means for reciprocating said nut, and means acting automatically as said nut is moved in one direction to prevent its turning on said post whereby it carries said post with it. 75

2. A jack comprising, in combination, a jack-post having a thread thereon so inclined to its axis that a nut screwed upon said thread may be turned by relative movement of said post and said nut along said axis, two nuts on said post relatively movable toward and away from each other, and 80 means whereby each is prevented from rotation while a relative movement of the post and the other nut takes place. 90

3. A jack comprising, in combination, a steeply threaded jack-post, two nuts upon 95 said jack-post, means for effecting relative movements of approach and separation of said nuts, and means operating in timed relation to said last mentioned means for alternately holding said nuts against turning 100 on said post.

4. A jack comprising, in combination, a jack-post having a thread thereon so inclined to its axis that a nut screwed upon said thread may be turned by relative movement of said post and said nut along said axis, a nut on said post, a carrier for said nut movable along said post and in which said nut may turn, means on said carrier to prevent turning of said nut as said carrier moves in one direction, whereby said carrier moves the jack-post with it, and means for retaining said jack-post in the position to which it is moved by said carrier. 105 110

5. A jack comprising, in combination, a jack-post having a thread thereon so inclined to its axis that a nut screwed upon said thread may be turned by relative movement of said post and said nut along said axis, two nuts on said post, means for moving 120 one of said nuts toward and away from the other, means for preventing the rotation of said movable nut as it is moved toward the other nut, whereby it carries the jack-post with it, and means for preventing the rotation of said second nut as said movable nut moves away therefrom, whereby the return of said jack-post is prevented. 125

6. A jack comprising, in combination, a jack-post having a thread thereon so in- 130

clined to its axis that a nut screwed upon said thread may be turned by relative movement of said post and said nut along said axis, a nut on said post, means for reciprocating said nut comprising a bearing in which said nut is confined with provision for turning movement about its axis and for limited movement along its axis, said nut and said bearing having coöperating clutching portions arranged to be moved into and out of operative engagement by the relative movements of said nut and said bearing along said axis.

7. A jack comprising, in combination, a jack-post having a thread thereon so inclined to its axis that a nut screwed upon said thread may be turned by relative movement of said post and said nut along said axis, two nuts on said post relatively movable toward and away from each other, and a bearing for each nut in which said nut is confined with provision for turning movement about its axis and for limited movement along its axis, said nut and said bearing having coöperating clutching portions arranged to be moved into and out of operative engagement by the relative movements of said nut and said bearing along said axis.

8. A jack comprising, in combination, a jack-post having a thread thereon so inclined to its axis that a nut screwed upon said thread may be turned by relative movement of said post and said nut along said axis, two nuts on said post relatively movable toward and away from each other, and a bearing for each nut in which said nut is confined with provision for turning movement about its axis and for limited movement along its axis, said nut and said bearing having coöperating clutching portions arranged to be moved into and out of operative engagement by the relative movements of said nut and said bearing along said axis, both of said bearing and nut couples moving to open position in the same direction along said axis.

9. A jack comprising, in combination, a steeply threaded jack post, two nuts upon said jack post, means for effecting relative movements of approach and separation of said nuts, means operating in timed relation to said last mentioned means for alternately holding said nuts against turning on said post, and means for preventing the operation of said holding means when release of said jack is desired.

10. A jack comprising, in combination, a steeply threaded jack post, two nuts upon said jack post, means for effecting relative movements of approach and separation of said nuts, means operating in timed relation to said last mentioned means for alternately holding said nuts against turning on said post, hand-operated means for effecting the relative movements of said nuts,

and treadle operated means for rendering one of said holding means inoperative.

11. A jack comprising, in combination, a steeply threaded jack post, a nut on said post, means for reciprocating said nut comprising a bearing in which said nut is confined with provision for turning movement about its axis and for limited movement along its axis, said nut and said bearing having coöperating clutching portions arranged to be moved into and out of operative engagement by the relative movements of said nut and said bearing along said axis, and means for holding said clutching portions out of clutching relation to release said jack.

12. A jack comprising, in combination, a steeply threaded jack post, two nuts upon said jack post, a stationary bearing member in which one of said nuts is rotatably mounted, a reciprocating bearing member in which the other nut is rotatably mounted and by which it may be moved toward and away from said first mentioned nut, and co-operating means upon each bearing member and the associated nut arranged to operate in timed relation to the reciprocating movements of said reciprocating member for alternately locking said nuts against rotation in their respective bearing members.

13. A jack comprising, in combination, a steeply threaded jack post, two nuts upon said jack post, a stationary bearing member in which one of said nuts is rotatably mounted, a reciprocating bearing member in which the other nut is rotatably mounted and by which it may be moved toward and away from said first mentioned nut, coöperating means upon each bearing member and the associated nut, arranged to operate in timed relation to the reciprocating movements of said reciprocating member for alternately locking said nuts to their respective bearing members, and means upon one of said bearing members whereby the operation of said locking means may be prevented.

14. A jack, comprising, in combination, a steeply threaded jack post, two nuts upon said jack post, means for effecting relative movements of approach and separation of said nuts, means operating in timed relation to said last mentioned means for alternately holding said nuts against turning on said post, and a stop on said jack post coöperating with one of said nuts to limit the movement of said jack post.

15. A jack, comprising, in combination, a jack post having a plurality of steep threads, two nuts upon said jack post, one of said nuts having a less number of threads than the other, and a stop located in that thread of the jack post which has no corresponding thread in the last mentioned nut.

16. A jack comprising, in combination, a

steeply threaded jack post, two nuts upon said jack post, means for effecting relative movements of approach and separation of said nuts, means operating in timed relation to said last mentioned means for alternately holding said nuts against turning on said post, and means for limiting the movement of the jack post constructed and arranged to travel freely through one of said nuts but to be stopped by the other.

17. A jack comprising, in combination, a steeply threaded jack post, two nuts upon said jack post, a stationary bearing member in which one of said nuts is rotatably mounted, a reciprocating bearing member in which the other nut is rotatably mounted and by which it may be moved toward and away from said first mentioned nut, coöperating means upon each bearing member and the associated nut arranged to operate in timed relation to the reciprocating movements of said reciprocating member for alternately locking said nuts against rotation in their respective bearing members, and a stop carried by said jack post and constructed and arranged to pass freely through the reciprocating nut into operative engagement with the nut carried by said stationary bearing member.

18. A jack comprising, in combination, a jack-post, means for moving said jack-post, means for retaining said post in the position to which it is moved by said moving means, and means carried by said jack-post constructed and arranged to pass one of

said aforementioned means in the operation of extending the jack and to engage the other to prevent over-extension of the jack.

19. A jack comprising, in combination, a jack-post, jack-post lifting means and jack-post retaining means both arranged to embrace said jack-post, and a stop carried by said jack-post adapted to pass one of said aforementioned means and to engage the other for preventing over-extension of the jack.

20. In apparatus of the class described, the combination with members arranged for combined longitudinal and transverse relative movement in substantial parallelism, and rectilinearly separable jack members respectively pivotally connected to said aforementioned members, whereby said jack may swing bodily during the relative movement of said aforementioned members, of moving and retaining means associated with the separable jack members and arranged for limited rectilinear movement therewith, and means mounted upon one of the first mentioned members and having operative connection with said retaining means in any swinging position of said jack for releasing said retaining means.

Signed at Holyoke, Mass., this 12th day of July, 1915.

DANIEL E. HENNESSY.
